UNITED STATES PATENT OFFICE.

EUGENE GRAVES ADAMS, OF LYNCHBURG, VIRGINIA, ASSIGNOR TO POSTAL INSURANCE CORPORATION, OF LYNCHBURG, VIRGINIA, A CORPORATION OF VIRGINIA.

SOUVENIR POSTAL CARD.

No. 853,853.

Specification of Letters Patent.

Patented May 14, 1907.

Application filed January 25, 1907. Serial No. 354,106.

To all whom it may concern:

Be it known that I, EUGENE GRAVES ADAMS, a citizen of the United States, residing at Lynchburg, Virginia, have invented 5 certain new and useful Improvements in Souvenir Postal Cards, of which the following is a specification.

My invention relates to souvenir postal devices and particularly to means for holding 10 a souvenir postal card as in a frame through which the picture is displayed and to means whereby the postal card may be readily withdrawn from the said frame.

My invention concerns also the utilization 15 of the postal card and the frame or rather the means for withdrawing the card from the frame as members of a two part insurance policy, as will be hereinafter referred to.

The invention is illustrated in the accompanying drawing, in which,—

Figure 1 is a front view of a souvenir postal card and the frame or envelop carrying the same. Fig. 2 is a view of the inner slide for withdrawing the postal card from its frame 25 or envelop, and Fig. 3 is a longitudinal sectional view through the envelop, the postal card and the slide or withdrawing device.

In these drawings, 1, indicates a postal card of ordinary form, 2 an envelop or frame 30 for carrying the postal card. This consists of a sheet 3 of paper or like material forming the back of the frame or envelop and having a front portion made up of an open frame consisting of the strips 4 extending along the 35 four sides of the envelop and reaching over the face of the postal card sufficiently to hold it yet leaving enough exposed to display the picture. This envelop or frame is open at both ends and within it is adapted to move 40 a slide or leaf 5 having one end turned up to overlie the edge of the postal card, and at its other end the slide is provided with a tab 6 adapted to enter a slit 7 in the back of the envelop or cover to thus hold the slide in 45 place.

When it is desired to withdraw the postal card, the tab is drawn upon thus withdrawing the slide and the upturned edge thereof acting against the edge of the postal card 50 will draw it from the outer envelop or frame.

The outer frame or envelop may be decorated in any suitable manner, particularly on those portions which form a frame-like portion for the picture on the card.

Besides providing means for the attractive 55 display of the souvenir card, the frame or envelop has other material advantages.

One of the greatest causes of loss experienced by the retail dealer of souvenir postal cards is the soiling and tearing of the cards 60 by persons who are choosing cards from the stock and who handle them in making their examination or choice and also the cards carelessly handled frequently drop to the floor and are thereby soiled. With my improved form of envelop the pictures are well 65 displayed, and the prospective purchaser, in handling the cards to make his choice, will grasp the envelop by the margin and thus the fingers will not come in contact with the 70 face of the card, nor will it be necessary to touch the card at all in order to draw it from the frame should the purchaser desire to do this, and therefore handling by the customer will 75 result neither in soiling nor tearing of the cards.

I use the inner slide and the postal card as members of a two part insurance policy. The slide will bear printed thereon the terms of the contract, spaces for the signature of the insurance company and of the 80 insured and bearing reference also to the souvenir postal card, and the fact that it bears an identical number with that on the slide or inner leaf and that it must be mailed in order to place the insurance in force. 85

The souvenir postal card will bear the number above mentioned and in addition it will bear a statement as follows:

"This card is part of the postal contract, bearing same number and issued the sender 90 by the Postal Casualty Company. Person addressed has interest as stated in the postal contract, which is in force for the 24 hours immediately following date of first postmark hereon. This card is number ____." 95

I do not wish to limit myself to the precise details of construction herein set forth as these may be changed.

What I claim is:—

1. In combination with the outer envelop 100 having an open front, an inner member or slide removably held by the outer member and a card held by the slide, said slide having a turned up portion engaging the card and overlying the face of the same, substantially as described.

2. In combination with the outer envelop 105 having an open face, an inner member or slide removably held by the outer member and the card held by the slide, said slide having a turned up portion overlying the card and fitting between the same and the 5 envelop, a tab on the slide the outer envelop having a slit engaged by the tab, substantially as described.

In testimony whereof, I affix my signature in presence of two witnesses.

EUGENE GRAVES ADAMS.
